(57) **CLAIM**

The ornamental design for the inner nozzle for plasma torch, as shown and described.

DESCRIPTION

FIG. 1 is a side view of an inner nozzle for plasma torch showing our design;

FIG. 2 is a front view thereof;

FIG. 3 is a rear view thereof;

FIG. 4 is a cross-sectional view taken along line 4-4 of FIG. 3;

FIG. 5 is a perspective view thereof;

FIG. 6 is an exploded view of a plasma torch, including an outer nozzle therefor, inner cap, electrode, plasma torch body, and the inner nozzle shown in broken lines for environment only, illustrating the position of the inner nozzle relative to the same and forming no part of the claimed design;

FIG. 7 is a side view of another inner nozzle for plasma torch according to our design;

FIG. 8 is a front view thereof;

FIG. 9 is a rear view thereof;

FIG. 10 is a cross-sectional view taken along line 10-10 of FIG. 9;

FIG. 11 is a perspective view thereof; and,

FIG. 12 is an exploded view of a plasma torch, including an outer nozzle therefor, inner cap, electrode, plasma torch body, and the inner nozzle shown in broken lines for environment only, illustrating the position of the inner nozzle relative to the same and forming no part of the claimed design.
